UNITED STATES PATENT OFFICE.

GUSTAV HILGENSTOCK, OF HOERDE, GERMANY.

TYUERE FOR BLAST-FURNACES.

SPECIFICATION forming part of Letters Patent No. 283,107, dated August 14, 1883.

Application filed July 12, 1883. (No model.) Patented in Germany August 17, 1880, No. 13 039.

To all whom it may concern:

Be it known that I, GUSTAV HILGENSTOCK, engineer, of Hoerde, in the German Empire, have invented certain new and useful Improvements in Tuyeres for Blast-Furnaces, (for which Letters Patent have heretofore been granted to me by the government of Germany, dated August 17, 1880, No. 13,039,) of which the following is a specification.

10 This invention relates to an improved construction of open tuyeres for blast-furnaces, technically known as "spray-tuyeres;" and the invention consists of a tuyere, open at the back and provided with an outwardly-flaring 15 exterior wall of elliptical shape, in combination with a spray-nozzle and with a frame that incloses the rear end of the tuyere, and is supplied with water by a U-shaped spray-pipe, the spray-water being drawn off at the lower 20 rear end of the frame or casing.

In the accompanying drawings, Figure 1 represents a vertical central section of my improved tuyere for blast-furnaces, and Fig. 2 is an end elevation of the same.

25 Similar letters of reference indicate corresponding parts.

The tuyere A is bent of U-shape and entirely open at its rear end, so that an open cooling-space, a, is formed around the inner 30 wall of the tuyere. The outer wall of the tuyere is made slightly flaring at the lower part, but with a considerable flare or inclination at the upper part, so that an exterior wall of nearly-elliptical outline is obtained.

35 The tuyere A is set into a casing, B, of the wall of the blast-furnace, the inner edge of the casing B being bent inwardly, so as to form a U-shaped rim, b, which is fitted exactly to the shape of the exterior wall of the tuyere, so as 40 to bind tightly and reliably thereon. The tuyere A, as well as the casing B, at the point of connection with the tuyere, is cooled by means of sprays of water, which are supplied by independent pipes C and D, that are hung to 45 proper clips d d' of the casing B. The water-pipe C terminates in the upper enlarged part of the tuyere A, and is provided with a large spray-nozzle, C', having an upwardly and laterally extending portion, e, and a lower scoop-shaped portion, e', (shown in Fig. 1,) so that 50 the exterior wall as well as the apex of the tuyere is uniformly and effectively supplied with

cooling-water. The water is shed along the sides and inclined bottom of the tuyere to the bottom of the casing B, and conducted to a gutter, B', attached to the outer edge of the bottom, whence it is carried off by a suitable pipe. 55

The water-supply pipe D of the casing B is made of U-shape, and perforated, the spray supplied thereby cooling the casing and tuyere at 60 their point of connection, which is in line with the inner wall of the blast-furnace, as shown in Fig. 1.

The advantages of my improved spray-tuyere for blast-furnaces are that no part of the 65 cooling-water can pass into the blast-furnace, which is one of the disadvantages of the closed tuyeres heretofore in use, in which the water forces its way into the furnace at that point where the tuyere becomes defective by use, so 70 that thereby the quality of the iron is deteriorated. The violent explosions, which are the result of the entrance of water into the blast-furnace, and the damage caused thereby are also entirely done away with by my open-spray 75 tuyere, in which any defect in the tuyere is instantly noticed by the escape of fire-gases or slag. Small cracks or defects are perfectly harmless, as the spray-water is prevented by the interior pressure of the wind from passing 80 to the interior of the furnace. As the tuyere is entirely open, even the smallest injury to the same can be instantly observed, when it can be easily and quickly exchanged whenever required. The expense of my improved tuyere 85 is considerably less than the old form of tuyeres, those of welded boiler-iron having proved very effective. They can be made by any skilled blacksmith near the furnace, so that one is not compelled to order them in iron-works. The tuyere can also be made of bronze 90 or tempered cast-iron. The spray-pipes can be applied without difficulty and any defect be quickly observed, as the tuyere can be observed up to the apex, and also tested by 95 feeling around the same with the hand, so that any possible danger from defective tuyeres can be fully and entirely avoided.

Having thus described my invention, I claim as new and desire to secure by Letters Patent— 100

1. A spray-tuyere for blast-furnaces composed of an open-back tuyere having an internal and a flaring exterior wall, a casing or frame fitted to the outer end of the tuyere, and

separate spray-pipes for the casing and tuyere, respectively, substantially as and for the purpose specified.

2. The combination, with an open-back tuyere having an internal and a flaring exterior wall, of a casing or frame having a bent rim at its inner end fitting around the tuyere, a spray-pipe with enlarged nozzle for the tuyere, and a U-shaped spray-pipe for the casing, substantially as set forth.

3. In a tuyere for blast-furnaces, the combination, with an open-back tuyere having an internal and a flaring exterior wall, of a spray-

nozzle having an upwardly and laterally extending portion and a lower scoop-shaped portion, whereby both the exterior wall and the apex of the tuyere are supplied with water, substantially as specified.

In testimony that I claim the foregoing as my invention I have signed my name in presence of two subscribing witnesses.

GUSTAV HILGENSTOCK.
